UNITED STATES PATENT OFFICE

1,924,079

MEANS FOR SUPPORTING RESISTOR COILS
IN ELECTRIC FURNACES

Donald Fraser Campbell, London, England, assignor to Ajax Electric Company, Inc., Philadelphia, Pa.

Application April 29, 1931, Serial No. 533,777,
and in Great Britain May 19, 1930

9 Claims. (Cl. 13—25)

The invention relates to means for supporting resistance coils in the side walls, roof, floor or doors of electric furnaces, etc., more especially in furnaces in which large spirals of heavy gauge 5 wire are to be inserted or supported.

In the usual known arrangements the contact between the wire and the firebrick impedes the free circulation of air, with the result that the temperature of the wire is considerably raised 10 at this part.

According to the invention, the brickwork is so formed that each spire of a coil is supported at two points, the coil being in contact with the brickwork along two lines, openings provided in 15 the brickwork allowing a free circulation of air at the parts where the resistors are placed.

Means are also provided to prevent currents of heated air from ascending directly to the roof of the furnace.

20 The invention is illustrated in the accompanying drawings in which:—

Fig. 1 is an end elevation and

Fig. 2 a plan of the supporting brick in the side wall.

25 Fig. 3 is a section on the line 3—3 of Fig. 4, and

Fig. 4 is a plan view, seen from below, of a roof brick.

30 Fig. 5 is a sectional elevation of the brickwork supporting the coils provided in the floor of the furnace.

Fig. 6 is a section on the line 1—1 of Fig. 7 and

35 Fig. 7 is a plan view, seen from below, of a roof brick.

Figure 8 is a transverse sectional view of a furnace wall constructed according to my invention and taken on the line 8—8 of Figure 9.

40 Figure 9 is a longitudinal section taken on the line 9—9 of Figure 8.

Figure 10 is a view similar to Figure 9 but showing a different bond arrangement.

Referring to Figs. 1 and 2, A represents a 45 brick of a side wall of the furnace, a the inwardly projecting end of the brick, B a spire of the resistor coil.

The part a is shaped, as shown, so that each spire B is supported at two points a', a'' and a free access of hot gases is provided by the openings a³.

Owing to the natural tendency in any furnace for the roof to become hotter than the floor, the following improvement in the usual side wall brick arrangement is made:

50 If the bricks were placed one on top of the

other with ordinary half brick bonding, the result would be a number of vertical channels or chimneys conveying a large amount of hot gases to the roof of the furnace. By adopting a bond of a 1/4 brick, the bricks are so arranged, that 60 the solid portion in one brick always acts as a baffle to the hot gases rising through the apertures in the brick immediately under it, and ensures a more uniform heating of the furnace chamber.

In Figs. 3 and 4 the roof brick C is provided with holes (not shown) in which the resistor coils B are inserted and make line contacts at intervals with the projections c', c''.

70 In Fig. 5 the resistor coils B similarly make line contacts with the bevelled edges d', d'' of adjacent floor bricks B.

Air can circulate freely in the spaces d below the resistors; these spaces also serving for receiving any scale, which can be easily removed 75 by blowing out or other means.

In the modification of the roof brick shown in Figs. 6 and 7, the resistors are supported on a continuous line contact, as in the hearth and 80 side resistors.

In Figures 8 and 9, I have shown a furnace side wall constructed with bricks A which are provided with spire supporting points a' and a'' upon a bracket part a.

85 I have adopted one-quarter brick bonding in Figures 8 and 9 to cause the solid portion of the bracket a to rest directly above the opening a³ in the brick below, to allow the rising gases to be deflected in their upward travel. This will prevent a large amount of hot gases from rising 90 directly to the roof of the furnace.

While vertical staggering of the opening is preferable, I find that desirable circulation may be obtained in the one-half brick bonding arrangement shown in Figure 10 in which the 95 apertures a³ are directly in line.

I claim:—

1. In a wall construction for electric heating furnaces, of the resistor type, a plurality of brick 100 having supporting brackets horizontally in line with each other to form supports and apertures within the brackets, in combination with resistor spires extending transversely with respect to the brick lying over the apertures and having engagement with the brick above the apertures 105 on opposite sides of the apertures.

2. In a wall construction for electric heating furnaces of the resistor type, a plurality of brick 110 having each a wall portion and a bracket portion which latter is apertured and offers engaging

- surfaces adjacent the aperture and on opposite sides thereof and a resistor spire larger in diameter than the spacing between the contact points, resting upon them and permitting flow of hot furnace gases through the apertures and through the spires in line with the apertures to facilitate hot gas circulation. 8
3. A heating and hot air circulating arrangement for a wall of an electric heating furnace of the resistor type, comprising a plurality of brick each having a wall portion and an outwardly and upwardly apertured bracket member, the bricks being arranged in superposed rows so that furnace gases passing through the aperture of one bracket can pass through the aperture of the adjoining bracket, in combination with resistor spires supported by the bricks above the apertures, whereby furnace gases heated by one spire can pass through the apertures to the spire above while gas is supplied from below the first spire through the apertures of the brackets upon which it rests. 10
4. A resistor spire in combination with a bracket supporting the spire at a plurality of points, apertured beneath the spire and outwardly and upwardly directed so that in combination with other brackets it forms a shelf, a second spire above the first and a bracket supporting the second spire apertured beneath the spire and with other brackets forming a second shelf, whereby the spire of each shelf is fed with furnace gases from the space above the shelf which lies below it and the furnace gases heated by each spire can divide outwardly and upwardly between shelves in one direction and upwardly through the apertures in another. 15
5. A side wall shelf, a plurality of brackets outwardly and upwardly extending, apertured, and each engaging the next bracket to form a continuous shelf in combination with bricks 20
- which are integral with the respective brackets and supporting them, and a resistor spire resting upon the shelf above the apertures and heating furnace gases passing upwardly through the apertures. 25
6. A plurality of brick or tile each having a body portion for wall position, and an intermediate upwardly and outwardly grooved, upwardly apertured, and upwardly and outwardly projecting bracket member forming a resistor support in combination with a plurality of brick or tile above the first plurality and having the apertures of the one plurality staggered with respect to those of the other. 30
7. An electric furnace wall brick or tile comprising a body portion adapted to form part of the body of a vertical wall and a grooved portion projecting into the furnace and having a vertical opening and supporting walls adjacent to the opening and a spire resistor resting on the supporting walls. 35
8. A furnace brick comprising a body portion adapted to be built into a furnace side wall and a resistor-supporting bracket integral therewith, projecting outwardly and upwardly, apertured, and having resistor supports adjacent to and above the aperture to hold the resistor away from the aperture. 40
9. A furnace brick comprising a body portion adapted to be built into a furnace side wall and a resistor supporting bracket integral therewith, projecting outwardly and upwardly, apertured, and having resistor supports adjacent to the aperture and above the aperture to hold the resistor away from the aperture, in combination with a spiral resistor permitting movement of furnace gases which pass through the aperture to pass transversely through the resistor. 45
